Atty.

UNITED STATES PATENT OFFICE.

WOLF ARBETTER, DECEASED, LATE OF BOSTON, MASSACHUSETTS; BY ESTHER H. ARBETTER, ADMINISTRATRIX, OF NEW YORK, N. Y.

BLINDSTITCH SEWING MACHINE.

Application filed February 24, 1921. Serial No. 447,536.

This invention relates to a sewing machine of the type well-known to the trade as felling or blind stitching machines which are used to stitch together two layers of cloth and which are characterized by making 5 stitches passing entirely through the upper layer but only part way through the lower layer of cloth as in the case of sewing linings into sleeves or sewing down the 10 folded fabric of a trousers leg or sleeve so as to avoid leaving a raw or unfinished edge on the garment.

In this class of machines as heretofore constructed it has been necessary to make 15 machines as right and left machines since the work could only be presented from one side of the work table, and in cases where it is necessary to present the work from the other side of the machine must be built with the 20 stitching and feeding mechanism reversed. It is the object of the present invention to provide a machine of this kind with such construction and arrangement that either right-hand or left-hand stitching may be 25 performed on the machine, and even specially difficult work such as the stitching in of linings or reenforcing patches to the seat and crotch of trousers may be satisfactorily performed on the same machine, thus adding 30 greatly to the range of work possible on a single machine and thereby lessening the number of machines required for the work in a garment factory.

To this end the invention consists, generally speaking, in the combination with a 35 vertically slidable carriage, of an upwardly extending post of relatively narrow cross section in which is mounted a downwardly yielding presser element acting to normally 40 press the work up against the overhead presser foot, combined with a vertically movable bender arranged to pass up through an opening in the yielding presser in order 45 to intermittently raise and crease or fold in the fabric to properly present the fabric to the stitching needle. This and other features of the invention will be particularly explained in the following specification and will be defined in the claims hereto annexed.

In the accompanying drawings I have 50 illustrated a simple construction and arrangement embodying the principles of this invention in which:

Figure 1 is a front elevation showing the supporting mechanism for the underneath 55 presser foot in operative relation to the bender and its actuating mechanism.

Figure 2 is a side elevation partly in 60 central section of the vertically sliding carriage and the associated bender.

Figure 3 is a plan view of the carriage member.

Figure 4 is a plan view showing the upper 65 end of the vertical guide-post.

Figure 5 is a plan view showing the relation of the underneath presser, the bender 70 and the guide-post.

In the accompanying drawings I have 75 illustrated only such parts of a blind stitching machine of well-known construction such as that shown in the patent to Bailey 1,091,619 as may be necessary to understand the construction and use of my improved mechanism. Since this invention relates only to the underneath work supporting 80 parts and the associated bender, I have attempted to indicate in the drawings only the position of the stitching needle and the feeding and cooperating upper presser foot with which the parts concerned in my invention have cooperative relation.

In practice of the invention according to the illustrative form shown in the drawings, I mount the usual vertically yielding 85 slideable carriage 4 in guideways formed in the vertical frame 1 of the machine which is surmounted by the usual table 2. The vertically yielding slideable carriage 4 is held in its slideway by the usual removable front plate 3, and is supported on a helical spring 90 7 whose tension is made adjustable by means of the hollow supporting nut 8 carried in a part of the frame work. At its rear the carriage is provided with a projecting boss 4^a adapted to be engaged by a lever *a* by means of which the carriage is depressed or lowered from operative position.

The upward movement of the carriage 4,

due to the tension spring 7, is limited from the fixed stop 9.

The carriage is provided at its upper end with a lateral offset portion or head 5 and projecting above this upper end of the carriage in a vertical hollow or tubular guide-post 10 which, in this case, is united firmly to the carriage by means of an end stud 10^a which passes through a receiving aperture in the carriage and is held in place by a clamping nut on its lower end. This construction is preferred in order to make the guide-post readily removable for substitutions or repairs, but the feature of removability is not essential to the proper operation of the device.

Inside the guide-post is mounted a plunger 11, whose upper end is provided with an enlarged head 12 adapted to form a downwardly yielding presser to press upward that portion of the cloth that is being stitched by the needle 50 in cooperation with the overhead presser foot and the feed dog 51. In the form shown, the presser foot plunger 11 rests upon helical spring 18 carried by the guide-post 10 so that the underneath work-supporting presser 12 is pressed up against the overhead presser foot and feed dog by a yielding pressure, said upward movement being limited by a fixed stop member which in this case is shown as a set screw 13 tapped into the guide-post and projecting into a slot 11^a in the side of the plunger 11. At its upper end the tubular guide-post is provided with upwardly extending lugs or projections 10^a on either side of the plunger board 10^b, arranged so as to closely engage the vertical sides of the presser 12 to firmly support and guide it in its operative position and to prevent any rotative or torsional movement of the presser. In this form one side face of the guide-post is left flat as shown at 10^c to form a flat vertical guide surface for the bender arm 14, whose reduced end 15 projects through a small aperture in that portion of the presser that overhangs or projects beyond the guide-post. For properly positioning the work the opposite ends of the presser are bevelled as shown at 12^a, 12^b.

The bender in this case comprises an angularly formed arm 14 having a straight middle portion adapted to slide vertically in a guide groove 6 formed in the horizontal head 5 of the main carriage 4. Adjacent to this slot 6, there is attached to the top of the head 5, by screws or otherwise, a slotted guide plate 16 whose slot extends to the forward edge of the plate and is closed by a front plate or part 15 detachably secured to the plate 16 so as to permit the ready removal of one bender and the substitution of another.

The bender is actuated by the usual mechanism comprising a spring-pressed plunger

20, mounted in bearings 30, formed on the front plate and yieldingly supported by an upwardly thrusting spring 25 whose upper end engages one of the collars 21, adjustably secured to the plunger. Between these collars 21 projects actuating stud 40 carried on the end of a cam-actuated rock-arm 41, by which the plunger 20 is depressed at the desired intervals in the operation of the machine. The bender arm 14 is pulled downwardly into operative engagement with the upper end of the plunger 20 by means of the contractile spring 19 whose other end may be fastened to any suitable part such as the upper collar 21. This causes the bender to follow the downward movement of the plunger induced by the cam lever 41, while the abutting of the ends of the two members acts to force the bender upward into action against the cloth when the position of the cam permits. The position of the cam is indicated in dotted lines on Figure 1.

By the above construction and arrangement the usual work-support having an opening or recess in its top for receiving the presser is entirely dispensed with, and a presser of narrow dimensions is projected so far above the machine table that it permits the presentation of the work from either the front or the rear side or in an angular position so that it is entirely practicable to blind stitch either right-hand or left-hand work or to perform special lining work such as the seat lining of trousers without difficulty. While the bender arm is shown as of angular construction it will be understood that this is not essential to the proper operation of the device, the bender being made in this form to facilitate quick removal and replacement, and in that connection also to prevent any torsional or twisting movement of the bender.

What I claim is:

1. A work-supporting carriage, a relatively narrow vertically bored guide-post projecting upward therefrom, a spring-pressed plunger having sliding engagement with said bore, said plunger having a relatively long and narrow head forming a work-supporting presser whose ends overhang the outer wall of the guide-post and whose sides are engaged with opposed upwardly projecting guide lugs formed on the guide-post, and a cooperating bender arranged to be movable through the presser into operative engagement with the work, substantially as described.

2. In a blind stitch sewing machine, the combination of a yieldingly supported carriage, a tubular guide-post of relatively small cross section detachably secured to said carriage, and projecting upwardly therefrom, a slidable plunger fitted into the bore of said tubular guide-post and

yieldingly pressed upward therein, said plunger, and a bender arranged to be moved through an opening in the presser head to act on the work, substantially as described. 10
5 guided between opposite upward extensions of the guide-post, means for limiting the upward spring-induced movement of the

In witness whereof, I have subscribed the above specification.

ESTHER H. ARBETTER,

Administratrix of Wolf Arbetter, deceased.
